GUSTAVE L. MILLER, OF GENESEO, ILLINOIS.

CORN-HUSKER.

1,253,508.

Specification of Letters Patent. Patented Jan. 15, 1918.

Application filed May 31, 1917. Serial No. 172,060.

To all whom it may concern:

Be it known that I, GUSTAVE L. MILLER, a citizen of the United States, and a resident of Geneseo, in the county of Henry and State 5 of Illinois, have invented new and useful Improvements in Corn-Huskers, of which the following is a specification.

My invention is an improvement in corn huskers, and has for its object to provide 10 a device of the character specified, which is especially adapted for permitting the ears to be snapped or broken from the stalk after they have been husked without strain on any part of the hand.

15 In the drawings:

Figure 1 is a perspective view of the improved husker in place on the hand;

Fig. 2 is a side view, with parts in section;

Fig. 3 is a transverse section;

20 Fig. 4 is a perspective view of one of the plates detached, with a part broken away;

Fig. 5 is a rear view of the husker;

Fig. 6 is a perspective view of a portion of the husker used as a breaking device;

25 Fig. 7 is a section on the line 7—7 of Fig. 6, looking in the direction of the arrows adjacent to the line.

In the present embodiment of the invention four plates 1, 2, 3 and 4 are provided 30 of semi-rigid material, and a plate 5 of thin pliable material, and the said plates are connected in a manner to be presently described.

Each plate 1, 2, 3 and 5 is secured to a sheet of flexible material, as, for instance, 35 leather, the plate 1 being connected to a sheet 6, the plate 2 to a sheet 7, the plate 3 to a sheet 8 and the pliable plate 5 to a sheet 9. The leather sheet 6 is adapted to underlie the plate 1 and to extend beyond the same 40 upon the front of the wrist, partially encircling the wrist, and a strap 10 is secured to one edge of this sheet, the free end of the strap being adapted to engage a buckle 11 on the opposite edge of the sheet. The sheet 9 45 to which the pliable plate 5 is secured is adapted to lie upon the back of the wrist, and the said sheet, together with the sheet 6, completely underlie the plates 1 and 5.

A strap 12 is secured between the plate 1 50 and the sheet 6, and the said strap is adapted to pass between the thumb and the hand and around the thumb, and through a slot 13 in a curved extension 14 from the plate 1, and to then bend back upon itself and pass about 55 the back of the hand to an engagement with

a buckle 15 on the sheet 8, the said buckle being at one end of the sheet.

A third strap 16 is secured to the outer end of the plate 4 to be presently described, and the said strap is adapted to pass back 60 of the hand to engage with a buckle 17 at the outer end of the sheet 8. The plate 1 is bent or curved to fit the base of the thumb and the adjacent portion of the palm of the hand, while the thin plate 5 is bent to fit the 65 base of the thumb and the edge of the hand and to extend over the back of the hand for some little distance from the thumb, as will be evident from an inspection of Fig. 5.

The plate 1 has a husking hook 18 which 70 is bent over and backwardly upon the plate, the bill of the hook pointing toward the wrist, and the said hook, when the husker is in place, is at about the base of the thumb, as shown in Fig. 1. The plate 2 has a lug 75 19 at its inner edge, and this lug is provided with openings 20 for engagement by a screw 21, to pivotally connect the lug to the plate 1. The plate 1 has an additional opening 22, and the openings 20 and 22 provide 80 for adjustment between the plates. The screw 21, as will be evident from an inspection of Fig. 2, is between the plate 1 and the sheet 6.

The plate 3 has an angular portion 23 85 which fits upon the inner face of the plate 2 at the outer edge thereof, and the said angular portion is adjustably connected with the plate 2 by means of screws 24, which engage slots 25 in the angular portion of 90 the plate 3, and openings 26 in the plate 2. It will be evident that by loosening the screws the plate 3 may be adjusted with respect to the plate 2 to fit the hand of the user. The plate 3, as shown more particularly in Fig. 3, fits against the inner side of the hand, from near the inner end of the palm to about the connection of the little finger with the hand. The outer end of the plate 2 is curved, as shown at 27, to fit 100 the inner face of the little finger when the said finger is curved, and this curved portion is provided with transverse corrugations 28 formed by embossing or indenting the material of the plate, and the free end of the 105 curved portion of the plate is bent over toward the palm of the hand, as shown at 27, to form a blunt edge, not, however, of sufficient curvature to be a hook or claw. The outer end of the plate 3 is also curved out- 110

wardly slightly, as shown at 30, to permit free movement of the fingers.

The plate 4 is a strap or bar, adjustably connected at its inner end to the plate 2, the outer end being connected to the strap 16 before mentioned. The adjustable connection between the plates 2 and 4 comprises a rivet 31 which pivotally connects the plate 4 to the plate 2, and a screw 32 which engages an opening in the plate 4 registering with a slot 33 in the plate 2. It will be evident that by loosening the screw 32 the plate 4 may be swung on its pivotal connection so that it will extend across between the thumb and the fore-finger at the proper point. The outer end of the plate 4 is curved transversely to fit this portion of the hand, and intermediate its ends the plate has a struck up blade 33* which opposes the curved portion 27 of the plate 2, and coöperates therewith in snapping or in grasping the ear of corn after it has been husked.

It will be noticed from an inspection of Fig. 1 that the plate 1 is notched deeply, as shown at 34 in Fig. 1, at about the middle of that side edge adjacent to the plate 2. This permits the portions on opposite sides of the notch to be curved at different radii. The plate 5 is of metal sufficiently pliable to permit it to conform to the shape and movement of the hand.

The entire device forms an instrument by which the husks are stripped from the ear, and by means of which the corn may be broken or snapped from the stalk, without undue strain on any part of the hand.

In use, with the parts in the position shown in Fig. 1 and adjusted to the hand, the husk is torn from the ear by the husking hook 18, after which the ear is grasped between the blade 33 and the curved portion 27 of the plate 2, and is snapped from the stalk. But little effort is required to snap the ear from the stalk, and the strain in so snapping the ear is evenly distributed at five points, that is, the up curved portion 27 of the plate 2, the transverse plate 4, the downward side of the plate 3, the sheet 5, and the strap 10.

By removing the plates 2, 3 and 4 from the plates 1 and 5, as shown in Fig. 6, that is, by removing the screw 21, the device may be used as a snapping device for breaking or snapping ears from the stalk without removing the husks, as, for instance, in the picking of green sweet corn and in snapping field corn for feeding. With this arrangement one end of a strap 36 is connected to the lug 19 by means of a bolt and nut 37, the other end of the strap being engaged with the buckle 15. This strap passes around the wrist at the base of the thumb as shown, and the ear may be grasped between the curved portion 27 of the plate 2 and the blade 33 of the plate 4.

I claim:

1. A device of the character specified, comprising a plate shaped to fit the palm of the hand at the wrist and the base of the thumb and having a husking hook near the base of the thumb, a second plate pivotally connected to the first plate at the side remote from the husking hook, said plate being of a length to extend approximately to the first joint of the little finger and being curved to fit the bent finger, a third plate adapted to fit alongside the edge of the hand remote from the thumb and having an angular extension adjustably connected to the second plate, a bar adjustably connected to the second plate at the side adjacent to the thumb and adapted to extend between the thumb and the fore-finger and having a plate extending toward the fingers, and means for securing the device in place, sundry of the plates having shields of leather between them and the hand.

2. A device of the character specified, comprising a plate curved to fit the base of the palm and base of the thumb and having a husking hook, a second plate pivoted to the first plate at the corners of the plates remote from the thumb, said second plate being of a length to extend to approximately the first joint of the little finger and being curved to fit the finger when bent, said second plate having a depending extension at the inner side of the hand, a bar connected to said second plate at the side adjacent to the thumb and having a plate opposing the curved portion of the second plate, and means for securing the plates in place on the hand.

3. A device of the character specified, comprising a plate curved to fit the base of the palm and base of the thumb and having a husking hook, a second plate pivoted to the first plate at the corners of the plates remote from the thumb, said second plate being of a length to extend to approximately the first joint of the little finger and being curved to fit the finger when bent, a bar connected with said second plate at the side adjacent to the thumb and having a blade for coöperating with the curved portion of the plate, and means for securing the plates on the hand.

4. A device of the character specified, comprising a plate curved to fit the base of the palm and base of the thumb and having a husking hook, a second plate pivoted to the first plate at the corners of the plates remote from the thumb, said second plate being of a length to extend to approximately the first joint of the little finger and being curved to fit the finger when bent, said second plate carrying at the side adjacent to the thumb a blade for coöperating with the curved portion, and means for connecting the plates to the hand.

5. A device of the character specified, comprising a plate curved to fit the base of the palm and base of the thumb and having a husking hook, a second plate pivoted to the 5 first plate at the corners of the plates remote from the thumb, said second plate being of a length to extend to approximately the first joint of the little finger and being curved to fit the finger when bent, said second plate 10 carrying at the side adjacent to the thumb a blade for coöperating with the curved portion, and means for connecting the plates to the hand.

6. A device of the character specified, 15 comprising a plate having means for securing the same on the hand at the inner edge of the hand, a plate having an extension lying along the side of the edge of the hand to hold the plate at the side edge of the 20 hand, said first named plate having a curved portion shaped to fit along the inner face of the little finger when the hand is partially closed, and carrying a blade at the opposite 25 side from the second plate for coöperating with the curved portion of the first named plate for snapping corn.

7. A device of the character specified,

comprising a plate having means for securing the same on the hand at the inner edge of the hand, a plate having an extension 30 lying along the side of the edge of the hand to hold the plate at the side edge of the hand, said first named plate having a curved portion shaped to fit along the inner face of the little finger when the hand is partially 35 closed.

8. A device of the character specified comprising a plate having means for securing the same on the hand at the inner edge of the hand, means in connection with the 40 said plate for engaging the edge of the hand to hold the plate at the side edge of the hand, said first named plate having a curved portion shaped to fit along the inner face of the little finger when the hand is partially 45 closed, and carrying a blade at the opposite side from the hand-engaging means for coöperating with the curved portion of the first named plate for snapping corn.
